US00D738844S

(12) **United States Design Patent**
Lee et al.

(10) **Patent No.:** US D738,844 S
(45) **Date of Patent:** ** Sep. 15, 2015

(54) **CELLULAR PHONE**

(71) Applicant: **LG ELECTRONICS INC.**, Seoul (KR)

(72) Inventors: **Hophil Lee**, Gyeonggi-do (KR);
Eunseok Choi, Gyeonggi-do (KR);
Seungbeom Park, Gyeonggi-do (KR)

(73) Assignee: **LG Electronics Inc.**, Seoul (KR)

(**) Term: **14 Years**

(21) Appl. No.: **29/477,688**

(22) Filed: **Dec. 26, 2013**

(30) **Foreign Application Priority Data**

Jun. 27, 2013 (KR) 30-2013-0033098

(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view thereof showing the state of opening;

FIG. 9 is a front view thereof showing the state of opening;

FIG. 10 is a rear view thereof showing the state of opening;

FIG. 11 is a left side view thereof showing the state of opening;

FIG. 12 is a right side view thereof showing the state of opening;

FIG. 13 is a top view thereof showing the state of opening; and,

FIG. 14 is a bottom view thereof showing the state of opening. The portion of the article shown in broken lines is for the purpose of showing environmental structure only and forms no part of the claimed design.

1 Claim, 11 Drawing Sheets
